WELL TESTER

Benjamin P. Nutter, Houston, Tex., assignor to Schlumberger Well Surveying Corporation, Houston, Tex., a corporation of Texas

Filed Dec. 24, 1963, Ser. No. 333,225
20 Claims. (Cl. 166—150)

This invention relates to apparatus for use in a well bore and more particularly to an apparatus for making multiple flow tests in a well bore.

Drill stem tests are normally performed by lowering a string of tools including a testing tool and packer to a desired depth of testing. The packer is set usually by applying force through the drill string, the packer isolating or packing-off the formation to be tested. Subsequently, a test valve in the testing tool is opened and closed by rotation of the drill string while the force on the drill string is maintained on the packer. The number of times that such a valve may be opened and closed is limited to one or two separate openings and closings and requires a given number of rotations for each operation. Rotation or torquing of the drill string for opening and closing operations is disadvantageous in that all the threaded connections in a tubing string may not be completely made up, therefore the given number of rotations may be taken up by the string of tubing without effecting an operation of the valve in the tool. Also, the tubing string may become lodged in the hole intermediate the length of the tubing so that the string of tubing twists above the lodged point without transferring the rotating motion to the tool. Subsequently, the tubing string may twist itself free and then make several uncontrolled revolutions on the lower part of the tubing string which may adversely affect the valve operation. These features of torquing movement involving the uncertainty of the number of turns of the tubing string give the operator little evidence of the position of the tool element in the operator to perform the various operations in the tool.

It is therefore an object of the present invention to provide a new and improved formation testing apparatus for making multiple flow tests in a well bore with apparatus which utilizes a vertical movement of the tubing string to perform the various operations in the tool.

Another object of the present invention is to provide an apparatus for making multiple tests of a formation utilizing longitudinal movement of the testing tool to perform the test operations.

A further object of the present invention is to provide a new and improved formation testing tool and an apparatus for packing-off the well bore in such a way as to facilitate longitudinal movement of the testing tool and yet maintain the packer in a set condition.

A still further object of the present invention is to provide a new and improved series of full-opening tools which may be used in combination with the new and improved formation tester.

With these and other objects in view, the present invention contemplates an apparatus for making multiple tests on a formation. More particularly, the apparatus includes a series of tools each including telescopically mounted members arranged to selectively move between longitudinally spaced operating positions, the series of tools including tester means, bypass means, jar means, safety joint means and packer means.

The tester means includes means permitting opening

2

and closing of a flow valve by longitudinal stroking movement of the drill string to place the telescoping members in spaced longitudinal positions and in each of such positions, force can positively be applied to the packer.

The bypass means includes means for quick closing of the valve and delayed or retarded opening so that the tester valve can be operated.

The jar, and safety joint means are provided to uncouple the tester and tubing string from the packer in the event of sticking and are compatible to the operation of the tester valve.

The packer means in one embodiment can be releasably latched against upward and downward movement in the well bore.

The novel features of the present invention are set forth in particularity in the appended claims. The present invention, both as to its organization and manner of operation together with further objects and advantages thereof, may best be understood by way of illustration and example of certain embodiments when taken in conjunction with the accompanying drawings in which:

FIG. 1 is a view in elevation of a series of well tools suspended from a string of pipe and arranged for going in a well;

FIG. 2 is an elevational view of an alternative apparatus connected in the series of tools for isolating the formation to be tested;

FIGS. 3A and 3B are detailed vertical sections of the well testing tool in accordance with the present invention;

FIG. 4 is a developed view of an index slot system used in the tester;

FIG. 5 is a detailed vertical section of a bypass valve;

FIG. 6 is a detailed vertical section of a safety joint;

FIG. 6A is a cross-sectional view of a safety joint taken along line A—A of FIG. 6;

FIG. 7 is a diagram which shows operating features of the safety joint;

FIGS. 8 and 9 are detailed vertical sections of a releasably locked packer device;

FIG. 10 is an enlarged detailed cross-sectional view taken along line 10—10 of FIG. 9 of a valve utilized in the packer device;

FIG. 11 is a vertical section of an alternative embodiment of the testing tool and bypass section;

FIGS. 12A and 12B are detailed vertical sections of an alternative combination of bypass and packer means.

Referring first to FIG. 1, a well tool 20 is arranged to be connected to the lower end of a string of pipe or tubing 21 and includes a tester section 22, a bypass section 23, a jar section 24, a safety joint section 25, a packer section 26, and a perforated anchor section 27. The anchor carries conventional pressure recorders 28 and has perforations 29 in the wall of the anchor section to permit fluid to flow into a bore in the packer mandrel and up through the string of tools. Two pressure recorders are provided, one recorder measuring pressure externally of the anchor and the other measuring pressure internally of the anchor.

In the operation of the well tool as shown in FIG. 1, the assembled tool 20 is attached to the string of pipe 21, and lowered into the well bore to the formation to be tested. The bypass section 23 of the well tool permits fluids in the well bore to bypass around the packer section 26 as the tool is lowered into the well bore and thereby permits a more rapid descent of the tool into the

well bore. When the anchor 27 is seated on the bottom of the borehole, further downward pressure on the tool will cause an elastomer packer element 125 to be expanded in the well bore to isolate the formation to be tested from the rest of the well bore. Formation fluids enter the tool through the perforations 29 in the anchor section and flow upwardly through the various tools to the tester section 22. Valves in the tester section are opened and closed to flow and shut in the formation fluids. The recorders housed in the anchor section are used to measure the pressure of the fluids during the flowing and shut-in periods.

FIG. 2 illustrates an alternative method of locating the well tool tester with respect to the formation to be tested wherein a conventional wall anchor 31 is used to position the tool 20 in the well bore at the desired depth and a pair of spaced packers 32 and 33 are utilized to straddle the formation to be tested. The wall anchor 31 is also used to set the packers.

Referring now to FIGS. 3A and 3B, details of the tester section of the tool will now be described. The tester section 22 generally includes a telescopically-arranged mandrel 36 and housing 41 respectively arranged for coupling between a pipe string 21 and the other sections of the tool. The tester mandrel 36 has a central bore 37 formed therein and intermediate of the length of the bore is a closure plug or barrier 38 (FIG. 3B) shear pinned at 39 to the mandrel and sealingly received therein. The housing 41 is divided into an upper housing section 42 and lower housing section 43 which are rotatably connected to one another by interlocking and cooperating flanges 46, 47 on the sections 42, 43. Flanges 46, 47 provide a swivel type connection so that the upper housing 42 can be rotated with respect to the lower housing 43.

The upper housing 42 has an index pin 48 projecting into an indexing slot system 49 formed in the mandrel 36. The indexing slot system is shown in a developed view in FIG. 4 and will hereinafter be more fully explained. The upper housing 42 also has an internal recess 51 with an inwardly-projecting spline or lug 52 disposed intermediate of the length of the recess. Housing spline 52 forms an abutment for an upper spline 54 projecting outwardly from the mandrel 36 into the housing recess 51. Splines 52, 54 are engaged and disengaged by operation of the slot system. Mandrel 36 further has a lower outwardly-extending spline 56 which is slidably received within a longitudinally-extending spline groove 57 in the interior of the lower housing.

The slot system as shown in FIG. 4 includes an upper pocket E, an intermediate pocket H and a pair of lower pockets G and A. The upper pocket and intermediate pocket are longitudinally aligned relative to one another while lower pockets G and A are equidistantly spaced to either side of the intermediate pocket H. Inclined and longitudinal slots are provided to connect the upper and lower pockets as well as the lower and intermediate pockets to one another and guide the index pin 48 in a predetermined manner. For example, if the index pin is initially in the lowermost pocket A, the following sequence of movements will produce the following described travel of the index pin:

(a) Upon downward movement of the mandrel, the index pin is guided from the lower pocket A to the upper pocket E.

(b) Upon upward movement of the mandrel, the index pin is guided from the upper pocket E to the lower pocket G.

(c) Upon downward movement, the index pin is guided from the lower pocket G to the intermediate pocket H.

(d) Upon longitudinal movement of the mandrel upwardly relative to the upper housing, the index pin is guided from the intermediate pocket H to the lower pocket A.

From this description, it will be readily grasped that

as the mandrel is moved longitudinally up and down, the index pin will follow a predetermined cyclic path. Hence, with the lower housing section 43, held stationary, the spline 56 and spline groove 57 maintain the mandrel 36 against rotation and the upper housing section 42 will be rotated by virtue of the index pin 48 following the slot system 49.

The slot system functions to place the upper housing spline 52 and mandrel spline 54 in engagement when the index pin is in the intermediate pocket H so that downward forces can be transmitted from the mandrel 36 directly to the housing 41 and specifically, lower housing section 43 via the splines 52, 54 and the upper housing 42. In this manner, the mandrel 36 can be pushed down on the housing 41 to apply weight to the string of tools therebelow. When the index pin is moved to the lower pocket A and then toward the upper pocket, the splines are meshed when the index pin moves between points B and C on the slot system (by virtue of relative rotational displacement) and a collar 58 on the upper end of the mandrel 36 is brought into abutting relationship with the upper end 59 of the upper housing 42 when the index pin is moved to the upper pocket E so that the mandrel can again be pushed down on the housing.

The lower housing 43, below the spline grooves 57, has a bore portion 61 with an enlarged internal diameter forming a cylinder 62 which receives a hydraulic delay piston 63 in the form of a sleeve between the cylinder wall and the mandrel. This annulus formed between the bore 61 and mandrel 36 is filled with a hydraulic fluid and sealed by floating annular piston and seal members 66 and 67, positioned at each end of the bore (FIGS. 3A, 3B). The delay piston 63 abuts on one end against an upper, annular valve seat 68 formed by a flange 69 on the mandrel 36. A delay valve spring 71 is disposed between a lower flange 72 on the mandrel 36 and the lower end of the piston 63. Spring 71 normally urges the piston 63 toward the seat 68 on the valve seat flange 69. The outer diameter of the piston 63 is less than the diameter of the bore 61 to form a restricted annular orifice 73. Hence, as the mandrel 36 is moved downwardly relative to the housing 41, the piston 63 seats on the valve seat flange 69 and the flow of hydraulic fluid into the cylinder 62 is metered between the piston 63 and cylinder wall 61 through the restricted annular orifice 73. This has the effect of delaying movement of the mandrel downwardly relative to the housing.

At the lower end of the bore 61 is a relief chamber 76 with a larger diameter so that when the piston 63 is moved into the relief chamber 76, a large fluid flow passage is provided between the piston and the housing. This permits the mandrel to "jump" or make a sudden movement downwardly at a terminal portion of its downward travel, causing the collar 58 to strike and engage the upper end 59 of the housing 41 sending a shock wave to the surface through the string of pipe to give the operator a surface indication that the index pin 48 is within the mandrel slot E.

On the other hand, when the mandrel is moved upwardly relative to the housing, the fluid above the piston 63 will move the piston downwardly relative to the mandrel to compress the spring 71. The inner wall of the piston is provided with longitudinal grooves 77 which permit the fluid to bypass between the piston 63 and the mandrel 36 so that the mandrel can be picked up relative to the housing relatively fast as compared to the downward movement of the mandrel.

Below the hydraulic delay system, the housing has a bore portion (FIG. 3B) which slidably and sealingly receives the lower end of the mandrel. The housing bore portion is recessed to provide an annular trap or sample chamber 78 between the housing 41 and mandrel 36. A flow port 79 is provided in the bore portion above the recess 78 and extends between the wall of the bore portion and an annular cavity 81 in communication with the

recess. Below the recess in the bore portion, the bore portion is similarly provided with a flow port 82 extending between the wall of the bore and an annular cavity 83 in the end of the housing.

The mandrel has spaced sealing elements 86 disposed to either side of a recessed portion 87, the sealing elements being arranged to seal the mandrel 36 relative to the bore above each of the housing flow ports 79, 82. The mandrel 36 also has a flow port 88 disposed above the upper seal and above the plug 38. When the mandrel is moved downwardly relative to the housing, the mandrel recess 87 between the mandrel sealing elements places the lower flow port 82 in communication with the sample chamber 78 and the upper flow port 79 in communication with the mandrel port 88.

The mandrel 36 is threaded on its lower end at 89 so that a portion 36a of the mandrel below the threaded joint may be removed. Removal of the lower portion 36a also removes the lower sealing element 86 and thereby renders the mandrel 36 incapable of sealing off the trap chamber 78. In this condition, when the mandrel 36 is moved up and down relative to the housing the lower flow port 82 is placed directly into and out of communication with the mandrel port 88 through upper flow port 79 in the housing.

In FIG. 5 the bypass section 23 of the tool is illustrated. The bypass section 23 includes a tubular mandrel 91 telescopically received within a tubular housing 92, the mandrel and housing respectively being adapted for coupling in the string of tools 20. A spline 93 on the upper part of the mandrel cooperates with a spline groove 94 in the bypass housing permitting relative reciprocation but preventing relative rotation therebetween. The spline 93 engages a flange 96 on the housing in an expanded position of the bypass section while a shoulder 97 on the mandrel engages the housing flange 96 in a contracted position. Intermediate of the housing is a bore portion 98 forming a cylinder which slidably receives a tubular sleeve piston 99 slidably mounted for limited longitudinal movement between a bypass flange 101 and seat flange 102 on the mandrel. The sleeve piston 99 has a slightly smaller diameter than the diameter of the cylinder bore thereby forming a restricted annular orifice 103. The ends of the annular chamber 98 formed between the mandrel and housing are closed by a pair of floating, compensation pistons 106, 107 which enclose a fluid within the chamber. When the mandrel 91 is moved downwardly relative to the housing 92, the fluid in the chamber moves the sleeve piston 99 upwardly and longitudinally-extending grooves 108 in the interior of the sleeve as well as passageways 109 in the bypass flange permit fluid to easily bypass the sleeve piston 99 and permit the bypass section to be rapidly moved to a contracted position. However, when the mandrel 91 is moved upwardly relative to the housing 92 to an expanded position, the fluid above the piston 99 causes the piston to seat on the seat flange 102 and fluid is metered through the restricted annular orifice 103 between the sleeve piston and cylinder bore. Hence, the mandrel movement upwardly relative to the housing is delayed and retarded.

The lower end of the housing has a bypass port 111 while the lower end of the mandrel has a sealing element 112 so that, in the contracted position of the mandrel and housing, the bypass port is closed by the sealing element 112 and the compensating piston seal 107.

FIGS. 6, 6A and 7 illustrate the safety joint section 24 of the tool. Referring first to FIG. 6, the safety joint section includes a tubular mandrel 113 telescopically received within a tubular housing 114, the mandrel and housing being adapted for coupling in the string of tools 20. A threaded nut 115 is positioned between the mandrel 113 and housing 114 and engages threads 120 formed on the upper end of the housing 114. The nut has an internal spline groove 123 formed thereon which cooperates with an external spline 124 formed on the mandrel 113. This spline arrangement provides for longi-

tudinal movement between the mandrel and housing of the safety joint but causes rotational movement of the mandrel 113 to be transmitted to the nut 115 to rotate the nut relative to the housing. A flange 145 formed on the mandrel 113 limits the upward longitudinal travel of the mandrel with respect to the housing. Two sets of lugs 146A, 146C and 146B, 146D are formed on the mandrel below the flange 145. The lugs in each set are spaced on the mandrel 180° from each other and the two sets are longitudinally spaced on the mandrel. Therefore, each of the lugs is spaced 90° from the adjacent lug and is positioned longitudinally therefrom. A longitudinal key 147 is positioned in the wall of the housing 114 and extends into the annular space between the housing and the mandrel. The key has a longitudinal dimension which is greater than the longitudinal distance between the sets of lugs 146B, 146D and 146A, 146C. An annular flange portion 148 formed in the inner bore of the housing 114 has annular recesses formed therein for receiving seal members 149. This flange portion having sealing members receives the lower end of the mandrel 113 in sliding engagement and seals the mandrel bore 151 from communication with an annular space 152 between the mandrel and housing which in turn communicates with the outside of the housing 114.

FIG. 7 shows in a developed view the relationship between the lugs 146A-146D and the key 147 as the safety joint is operated. In the starting position shown in the top diagram the lugs and key are positioned as shown in the elevational view of FIG. 6, and cross-sectional view FIG. 6A, that is, with the lug 146A positioned abutting the key 147. The second diagram shows that if the mandrel 113 is raised relative to the housing 114 and rotated counterclockwise the lug A will be positioned above the key and will rotate with the mandrel until the lug B abuts the key 147. The third diagram shows that subsequently if the mandrel 113 is lowered relative to the housing the lug B will drop below the key 147 and upon rotation of the mandrel counterclockwise, will rotate relative to key 147 until the lug C abuts the key 147. Thereafter, another upward movement on the mandrel and counterclockwise rotation of the mandrel will raise the lug C above the key and rotate it relative to the key until the lug D abuts the key 147, thus completing 270° of rotative movement of the mandrel in the four diagrams shown in FIG. 7. As the mandrel 113 is rotating relative to the housing 114 the splines 123, 124 located on the nut and mandrel, respectively, are meshed to rotate the nut 115 with the mandrel 113. If the longitudinal rotative movement described relative to FIG. 7 is repeated enough times the nut 115 will be unscrewed from the mandrel 114 whereupon the mandrel 113 will be free to be withdrawn from the housing 114 thereby releasing or freeing tool members positioned in the tool string above the safety joint for withdrawal from the well bore.

The packer assembly is shown in FIGS. 8-10. The packer assembly 26 includes telescopically-mounted mandrel 116 and housing 117 which are respectively arranged for coupling to the tool sections above and below the assembly. At the lower end of the mandrel is a flange 118 and an annular back-up plate 119. An annular elastomer packing element 125 is received on the mandrel between the lower back-up plate and an upper back-up plate 121. The housing has a flange 122 abutting the upper back-up plate. It will be appreciated that if the housing 117 is moved downwardly relative to the mandrel 116, the packing element 125 can be expanded to engage the wall of the well bore as shown in FIG. 9.

In the upper part of the mandrel and housing is a system for releasably retaining the packer element in an expanded condition. For this system the mandrel has upper 126 and lower flange portions slidably and sealingly received in the housing and forming a recess or chamber 128, 129 therebetween, the chamber being filled with a hydraulic fluid. The housing has an inwardly-extending

piston 131 which is slidably received in the chamber and forms upper 128 and lower 129 recess portions. Upper 132 and lower 133 passageways extend longitudinally through the piston to a valve 134. It will be appreciated that if the valve is opened in the position shown in FIG. 8, connecting the upper 132 and lower 133 passageways to one another, fluid will pass from the lower recess portion 129 to the upper recess portion 128 when the housing 117 is moved downwardly relative to the mandrel 116 to the position shown in FIG. 9. With the packer

The fluid leakage mentioned above is for the purpose of obtaining release of the valve eventually should a malfunction occur. Thus the packer is never irretrievably set in the well bore.

5 The differential pressures to control the spool valve are obtained in a manner which will hereinafter be more fully explained.

The operation of the apparatus of FIGS. 3-10 may best be understood by use of the following table in connection with the description following.

	Going in	Setting packer	Open tester	Close tester
Tester section	Expanded	Expanded, slowly moving to contracted.	Contracted	Expanded to intermediate position.
Index position	A	A toward C	C to E	E to G to H
Shoulder 58	Not engaged	Not engaged	Engaged	Not engaged
Housing end 59	do	Moving to meshing relationship.	Not engaged	Engaged
Splines 52, 54	do	do	Open	Closed
Test port 88	Closed	Contracted	do	Do
Sample chamber 78	do	Closed	Contracted	Contracted
Bypass section 23	Expanded	Contracted	Closed	Closed
Bypass port 111	Open	Closed	Contracted	Contracted
Packer section 25	Expanded	Contracted	Expanded	Expanded
Packer element 125	Contracted	do	Closed	Closed
Valve 134	Open	Open	do	do

element 26 expanded, closing of the valve 134 and taking 30 the upper 132 and lower 133 passageways out of communication will trap fluid in the upper recess portion 128 and prevent the housing from moving upwardly relative to the mandrel.

The valve system includes a port 135 in the mandrel 35 116 opening to a recessed portion 136 of the piston between spaced seals 137 and a control port 138 in the piston opening to the valve 134. As shown in FIG. 10, the valve includes a sleeve 141 retained in a bore 142 of the housing, the sleeve 141 having a first annular groove 143 and ports in communication with a first passage 144 and a second annular groove and ports 156 in communication with a second passageway 157. It will be appreciated that FIG. 10 illustrates both upper 132 and lower 133 passageways for convenience of understanding although one of the passageways would not be seen in the section view. The illustration also demonstrates that the upper and lower passageways are offset relative to one another at their access points to the valve.

A bore 158 in the sleeve 141 opens at one end to the exterior of the tool and at the other end to the control port 138. Received in the sleeve bore is a spool type piston 159 arranged for movement between a position placing the upper and lower passageways 132, 133 in communication and a position where the upper and lower passageways are isolated from one another. A spring 161 is provided to normally urge the piston to a position placing the passageways in fluid communication with one another. The piston in the position illustrated has a first portion 162 closing off the sleeve ports leading to passageway, the first portion, however, having a slightly smaller diameter than the bore of the sleeve permitting some fluid leakage to occur. When fluid pressure exterior of the housing is greater than fluid pressure at the control port 138 (which is connected by the piston recess 136 and mandrel port 135 to the interior of the mandrel) and the force of the spring 161, the piston 159 will assume the illustrated position where the first portion 162 of the piston isolates the first 144 and second 157 passageways from one another. When the fluid pressure exterior of the housing is less than the fluid pressure at the control port 138 and the force of the spring 161, the piston is shifted so that a recessed portion 163 of the piston places passageways 144, 157 in communication with one another.

Condition 1

In going-in the well bore, the various elements and tool parts are in the conditions above noted. In the packer assembly, the valve 134 (FIG. 10) is open because the pressure of the fluids within the packer mandrel 116 are the same as the pressure of the fluids on the exterior of the tool so that the spring 161 places the spool piston 159 in a position where the upper and lower passageways 132, 133 are in fluid communication.

40 The bypass 23 is held in an expanded position by the weight of the tool attached to the bypass housing 92 so that the bypass port 110 is open and fluid can pass through the packer mandrel 116 and return to the well bore via the bypass port 111.

In the testing section, the sample chamber 78 and test ports are closed while the index pin is disposed in the 45 pocket A.

Condition 2

Upon reaching the level of the test, the packer element 125 is expanded. This occurs because the packer 50 mandrel 116 is fixed relative to the well bore. Fixing the mandrel may be by contact with the bottom by the perforated anchor 27 or by setting a hook wall anchor as shown in FIG. 2. It should be noted that for use of a hook wall packer, the conventional J slot control can be operated because all of the sections are spline connected to permit rotation. While splines are not shown in the packer assembly 26, it will be appreciated that this connection can easily be furnished between the mandrel 116 and upper housing 117.

60 As stated heretofore, the packer mandrel is fixed and a downward motion on the string of pipe is transmitted through the tool sections to move the upper packer housing 117 relative to the packer mandrel 116 and expand the packer element 125. As the packer element expands, 65 the bypass section 23 contracts to close the bypass port 111 bringing the bypass mandrel shoulder 97 into abutment with the bypass housing. In the tester section the fluid in the delay system is trapped below the piston 63 and very slowly meters through the restricted orifice 73. At this time, the index pin is moving from pocket A 70 toward pocket C and rotating the upper housing 42 to place the splines 52, 54 in meshing relationship to one another. Well before the tester section becomes contracted the packer is fully expanded and the bypass is 75 closed.

Condition 3

After the packer is fully expanded, the delay piston 63 in the tester section reaches the recessed portion 76 and very quickly permits the tester mandrel and housing to contract and very quickly opens the mandrel test port 88 and sampling chamber 78 to the bore of the well tool which extends down to the perforated anchor 27 below the expanded packer. This quick motion is apparent at the earth's surface as was heretofore described and gives an indication to the operation that the tool is properly operating. Because the interior of the string of pipe and the formation pressures are considerably less than the hydrostatic pressure of the well fluid above the expanded packer, the valve 134 in the packer is closed trapping fluid in the upper recess 128 of the packer assembly. At this time, the tester mandrel shoulder 58 engages the upper housing end 59, the bypass shoulder 97 engages the bypass housing 92 and downward pressure on the string of pipe can be maintained on the packer element to ensure that it will be fully expanded. During this condition, the index pin has traveled from position C into the slot E.

Condition 4

After fluid has flowed for a sufficient period of time, say fifteen minutes, the tester is closed for, say, five minutes to obtain a shut-in pressure. To close the tester the string of pipe is picked up a sufficient distance to index the pin from the upper pocket E to the lower pocket G and then set down to index the pin to the intermediate pocket H.

In picking up the string of pipe, the delay valve in the tester opens to permit quick bypass of fluid and movement of the tester section to the expanded condition. At the same time, the delay valve in the bypass retards movement of the bypass to an expanded position and the closed valve 134 in the packer assembly prevents release of the expanded packer element 125. The splines 52, 54 in the tester section are meshed once again and the mandrel spline 54 disposed above the housing spline 52. Thus, when the string of pipe is set down and the index pin goes to the intermediate pocket H the splines are brought into abutment and direct force on the string of pipe is once again directly transmitted to the bypass and packer sections to maintain the packer element expanded to close off the formation while the pressure of the formation fluids is measured.

When the tester, with the mandrel end 36A threaded at 89 to the tester mandrel, is closed, a fluid sample is trapped in the sample chamber 78. If it is desired to retrieve the well tool, picking up the drill pipe moves the index pin from pocket H to pocket A.

On the other hand, it is often desirable to repeat the above sequence of operations a number of times which permits formation conditions to be determined by analysis of sequential shut-in and build-up pressure recordings. This may be done by repeating the up and down movements of the tester mandrel as set forth above.

To determine when the fluid recovery is formation fluids, a gas flowmeter 19 (FIG. 1) is connected to the string of pipe at the surface. As fluids enter the string of pipe the displacement of air in the pipe is indicated by the flowmeter. At a point where the formation fluid flow stabilizes the gas flow becomes constant indicating completion of the test.

Tool retrieval

In order to retrieve the tool string 20 and the fluid sample which may be trapped in the chamber 78 when end section 36a is attached to the tester mandrel, the packer element 125 must be contracted to release the tools from the well bore. This step may be accomplished by picking up on the tool string to close the tester valve and trap a fluid sample at formation pressures. Thereafter, the bypass mandrel 91 is lifted up relative to the

bypass housing 92. A continued lifting force on the mandrel 91 will permit sufficient fluids to leak by the bypass piston 99 through the restricted orifice 103 to allow the mandrel and seal 112 to uncover the bypass port 111. The opening of port 111 subjects the inner bore of the tool sections to the hydrostatic pressure of the well fluids thereby increasing the inner bore pressure and consequently communicating the increased pressure with the control port 138 of the packer. This pressure in turn acts with spring 161 to move the piston 159 forward and open the valve 134 to connect the upper and lower passageways 132 and 133. The valve opening permits expanding movement of the packer mandrel and housing to release the packer element 125 from compression and engagement with the well bore.

Further upward movement of the tubing string will withdraw the tool string from the well bore. If for some reason the tool or string of pipe should become lodged or stuck in the well bore a jar section is provided in the tool string to permit a jarring force to be applied to the tool string. The jar section 24 (FIG. 1) may be of the type set forth in a co-pending application for "Well Jar Systems," Ser. No. 280,829 now Patent No. 3,251,426, and owned by the assignee of the present invention.

If the tool string should not become dislodged from the well bore by the use of the jar, the safety joint 25, described heretofore in the description, may be utilized. The tubing string is rotated above the safety joint to release the upper part of the string for retrieval to the surface. In order to affect the loosening of the threads in the safety joint or other pipe joints below the safety joint, it may be necessary to lower an explosive element or string shot into the full open bore of the tool string to the level of the joint whereupon the shot is detonated to loosen the joint for subsequent unthreading by rotation of the tubing string. The knock out plug 38 which serves the purpose of blocking the tester section mandrel bore 37 during flow testing of the well may be removed by dropping an object in the bore of the tubing string which object serves to shear the pin 39 to knock out the plug 38. This opens the bore for lowering of the string shot to the safety joint section 25.

After retrieving the tool to the surface, it is necessary to analyze the sample trapped in the chamber 78 at the conditions under which it was trapped. To effect this purpose, a plug 85 is threadably received in the wall of the lower tester housing 43 (FIG. 6B). Manipulation of the tester members will permit sealing off of this plug port for removal of the plug and insertion of test instruments while maintaining the sample at reservoir conditions. Subsequently, the tester mandrel is moved to uncover the plug port and place the instruments in communication with the sample chamber for analysis of the trapped fluid.

The applicant has set forth a preferred embodiment of the apparatus to perform the multiple testing operation. There are many forms of apparatus which could be utilized to perform this method of operation. One such alternative embodiment of a tester and bypass section of the tool is shown schematically in FIG. 11.

The tester and bypass section shown in FIG. 11 includes a tester section 173 which has an index system and spline arrangement similar to that described with reference to the tester embodiment shown in FIGS. 3A and 3B. Likewise, the hydraulic delay piston shown in the embodiment in FIGS. 3A and 3B may be utilized in this embodiment although not shown in FIG. 11. The tester section further has an orifice plug 174 positioned in a tester mandrel 176. A tester housing 177 likewise has a plug 178 positioned in a bore formed in the housing and connected to the housing by spider-fingers 179 arranged around the bore of the housing. These fingers, being spaced apart, permit fluid flow around the plug 178. A bore formed in the tester mandrel is sized to slide over the plug 178 positioned in the tester housing

and a seal member 181 which is formed on the plug 178 serves to seal the bore of the tester mandrel from the bore of the tester housing.

In the operation of this tester the tester mandrel is raised by an upward movement on the drill pipe to expose the bottom of the tester mandrel bore to formation fluids flowing into the tester housing from below as indicated by the arrows in FIG. 11. To close the tester, downward movement on the tester mandrel places the tester mandrel bore over the plug 178 and seal member 181 to seal the tester mandrel bore from fluids flowing into the tester housing.

The bypass section 186, which is suspended below the tester section 173, has a mandrel 187 that is hreadedly secured at its upper end to the bottom of the tester housing, the lower end portion being telescopically connected to a bypass housing 188 by any suitable means (not shown), for example the spline, groove and flange arrangements shown in FIG. 5. A bypass housing 188 has bypass ports 189 formed therein. A seal 191 which is positioned on the bypass mandrel serves to seal off the bypass ports 189 when the bypass mandrel is in a down position as shown in FIG. 11. Upward movement on the bypass mandrel will position the seal 191 above the port 189 to provide fluid communication from the interior of the bypass section to the annular space in the well bore. A packer 192 which is positioned below the bypass 186 may depend for its expanded condition upon the bypass valve or port 189 being closed to prevent hydrostatic pressure in the well bore from entering the interior of the bypass housing. Therefore, the maintenance of the bypass in a closed position is important and will be explained.

The bypass is maintained in its closed position by the action of fluid forces on exposed areas of the tester and bypass members (FIG. 11). After the bypass is closed, the forces, which act down on the tester housing and bypass mandrel, are maintained greater than the forces acting up on the tester housing and bypass mandrel. The forces acting down can be calculated by multiplying the hydrostatic pressure in the well bore P_h times the difference between the area of the tester housing and the area of the tester mandrel ($A_1 - A_2$). The forces acting up on the system may be calculated by multiplying the hydrostatic pressure P_h times the area of the tester housing minus the area of the bypass mandrel ($A_1 - A_3$) plus the formation pressures P_f times the area of the bypass mandrel minus the area of the tester mandrel ($A_3 - A_2$). The latter calculation, $A_3 - A_2$, represents the effective area of the tool subjected to formation pressures which is in effect the difference in areas between the top and bottom of the bypass mandrel 187 that is exposed to formation fluid. The total force F_d down may be calculated by subtracting the forces up from the forces down as shown in the following equation:

$$F_d = P_h(A_1 - A_2) - P_h(A_1 - A_3) - P_f(A_3 - A_2) \quad (1)$$

$$F_d = P_h(A_3 - A_2) - P_f(A_3 - A_2) \quad (2)$$

$$F_d = (P_h - P_f)(A_3 - A_2) \quad (3)$$

Therefore, if the hydrostatic pressure in the well bore is maintained greater than the formation pressure, the forces acting on the tester and bypass after closure of the bypass valve will serve to maintain the bypass valve in closed position.

In order to open the bypass, an upward acting force must be applied to the tester housing and bypass mandrel which will overcome the predominant downward forces. This is accomplished by applying lifting force on the tubing string which is sufficient to shift the balance of forces in an upward direction.

It may be appreciated from the foregoing discussion of this alternative bypass system that longitudinal upward and downward movements of the tubing string to manipulate the multiple test section would not open the bypass but rather an upward force calculated to shift the

balance of forces must be applied to the bypass mandrel to open the bypass.

An alternative bypass and packer which is the subject of applicant's Patent No. 3,020,959 for "Well Packers" is shown in FIGS. 12A and 12B. This packer and bypass tool includes a mandrel 201 and a housing 202. A series of openings 203 in the mandrel wall provide a bypass for fluids around a packer element 204, when expanded, which is positioned on the outer wall of the housing 202. The mandrel is slidably received within the housing and upon downward movement of the mandrel with respect to the housing, seals 206 positioned in the mandrel above the bypass ports 203 are received within a recess 207 formed in the upper end of the housing to seal off the bypass ports from the well bore above the packer element 204. The same downward movement of the mandrel is used to set the packer. However, before downward movement of the mandrel relative to the housing is possible, it is necessary to rotate the tubing string to the right while lowering it to screw the mandrel through a split nut 209 received between the mandrel and housing. After the bypass has closed, the further downward movement on the mandrel is transferred to an upper housing member 211 and this section is moved relative to a lower housing 212 which resists longitudinal movement because of the contact of a friction pad 213 with the wall of the well bore. Thus, downward movement is transmitted through the upper housing 211 to an expander 214 which wedges slips 216 outwardly into gripping contact with the casing. Thereafter, motion of the expander and attached lower packer shoe 217 ceases and further downward motion of the mandrel assembly serves to compress the elastomer packer element 204. During the downward travel of the mandrel assembly buttress threads 218 formed on the mandrel ratchet through an upper split nut 219. The upper split nut acts in the opposite direction from the lower split nut 209 in that an upward pull on mandrel 208 will not produce movement thereof relative to the housing assembly. Upward motion of the mandrel 208 when the packer is set is limited by the engagement of the upper edge on the split nut 219 with a shoulder 221 formed on the housing. This locking of the mandrel is advantageous in that an upward pull on the mandrel cannot open the bypass ports or tend to unseat the packer. This is particularly useful when the packer is used in conjunction with an auxiliary tool such as a formation tester which requires longitudinal movement of the tubing string to operate the tester.

To unseat the packer it is necessary to first release the threaded engagement between the upper split nut 219 and the mandrel assembly. This is accomplished by rotating the tubing string to the right and simultaneously exerting a pull thereon. When disengaged, the mandrel assembly is pulled upwardly to expose the bypass ports to the well fluid thereby equalizing the pressure above and below the packer. Thereafter upward motion of the mandrel assembly is transmitted to the upper housing 211 to exert tension on the packer element 204 and return it to its uncompressed original shape. At the same time the expander slips 216 are retracted and the mandrel buttress threads 218 ratchet back through the lower split nut. The packer may now be retrieved from the well.

Should the wall engaging portions fail to unseat properly, a jar and a safety joint may be provided in the tool string to facilitate retrieval of the well tool in such emergencies. The packer and bypass tool is full-opening to allow for lowering of or retrieval of other small diameter tools through the bore of the tool.

Different well testing apparatus is usually designed for use in open and cased well bores. Although this invention is primarily directed to apparatus for testing open well bores it will be appreciated that features of the present invention can have application for testing apparatus for cased well bores.

While particular embodiments of the present invention have been shown and described, it is apparent that changes and modifications may be made without departing from this invention in its broader aspects and, therefore, the aim in the appended claims is to cover all such changes and modifications as fall within the true spirit and scope of this invention.

What is claimed is:

1. Apparatus for testing earth formation conditions in a well bore containing well fluids comprising:
flow conduit means extendible in a well bore to earth formations to be tested and including a string of pipe, tester means, and packing-off means, said packing-off means being below said tester means and arranged to selectively isolate a section of the well bore from the well fluid therein,
said tester means including telescoping tubular members,
one of said members having rotatively coupled parts,
one of said parts having longitudinally spaced abutments,
the other of said members having an abutment, and indexing means between said one part and said other member for selectively positioning said other member abutment on one of said part abutments by longitudinal movement of said other member and rotation of said one part.
2. Apparatus for testing earth formation conditions in a well bore containing well fluids comprising:
packing-off means dependently coupled to tester means,
said packing-off means being arranged to selectively isolate a section of the well bore from the well fluid therein,
said tester means having telescopically arranged members adapted for coupling between a string of pipe and said packing-off means and longitudinally movable between contracted and expanded positions,
valve means in said tester means for selectively opening said tester means to fluid flow in one of said positions and closing said tester means to fluid flow in the other of said positions,
one of said tester members having parts rotatively secured to one another,
one of said parts and said other member respectively having abutment means providing at least two longitudinal positions of abutment, and
means interconnecting said one part and said other tester member for selectively positioning said abutment means in said positions.
3. Apparatus for testing earth formation conditions in a well bore containing well fluids comprising:
packing-off means dependently coupled to tester means,
said packing-off means being arranged to selectively isolate a section of the well bore from the well fluid therein by the application of a downward force,
said tester means having telescopically arranged members adapted for coupling between a string of pipe and said packing-off means and longitudinally movable between contracted and expanded positions,
valve means in said tester means for selectively opening said tester means to fluid flow in one of said positions and closing said tester means to fluid flow in the other of said positions,
one of said tester members having parts rotatively secured to one another,
one of said parts and said other member respectively having abutment means providing at least two longitudinal positions of abutment, and
indexing means interconnecting said one part and said other tester member for selectively positioning said abutment means in said positions whereby a downward force can be applied in each of said positions.
4. Apparatus for testing earth formation conditions in a well bore containing well fluids comprising:
packing-off means dependently coupled to tester means,

said packing-off means being arranged to selectively isolate a section of the well bore from the well fluid therein by the application of a downward force,
said tester means having telescopically arranged members adapted for coupling between a string of pipe and said packing-off means and longitudinally movable between contracted and expanded positions,
valve means in said tester means for selectively opening said tester means to fluid flow in one of said positions and closing said tester means to fluid flow in the other of said positions,
one of said tester members having parts rotatively secured to one another,
one of said parts and said other member respectively having abutment means providing at least two longitudinal positions of abutment,
indexing means interconnecting said one part and said other tester member for selectively positioning said abutment means in said positions whereby a downward force can be applied in each of said positions, and
means for delaying telescopic movement of said tester members to a position opening said valve means.

5. A well tool for use in a well bore,
a first tubular member,
a second tubular member having a longitudinal opening therethrough and slidably received within said first tubular member,
barrier means in one of said members dividing said longitudinal opening through said member into an upper and lower passageway,
means for limiting relative movement between said members for at least two longitudinal positions,
said means including spaced abutment means arranged for contact in spaced longitudinal positions for transmitting downward forces in said spaced longitudinal positions,
valve means in said members operative for connecting said upper and lower passageways in one of said positions to permit fluids to pass from one of said passageways to the other of said passageways and operative in said other position for closing said passageways from fluid communication with one another,
means for positioning said abutment means by reciprocating motion between said first and second tubular members, and
delay means for retarding longitudinal movement between said first and second tubular members when moving toward a position where said valve means permit the passage of fluid between said passageways.
6. A well tool for use in a well bore,
a first tubular member,
a second tubular member having a longitudinal opening therethrough and slidably received for telescopic movement within said first tubular member,
barrier means in one of said members dividing said longitudinal opening through said second tubular member into an upper and lower passageway,
means coengagable between said members for limiting relative movement between said members for at least two longitudinal positions,
said means including spaced abutments arranged for contact in spaced longitudinal positions for transmitting downward forces in said spaced longitudinal positions,
valve means in said members operative for connecting said upper and lower passageways in one of said positions to permit fluid to pass from one of said passageways to the other of said passageways and operative in said other position for closing said passageways from fluid communication with one another,
means for positioning said abutment means by reciprocating motion between said first and second tubular members, and
delay means for retarding longitudinal movement be-

tween said first and second tubular members when moving toward a relative position where said valve means connect said passageways,
said delay means having shunt means permitting relatively fast telescoping movement between said first and second tubular members when moving toward the relative position where said valve means close said passageways.

7. Apparatus for use in a well bore, comprising:

a first tubular member,
a second tubular member having a longitudinal opening therethrough and slidably received within said first tubular member,
removable closure means in said second tubular member dividing said longitudinal opening therethrough into an upper and lower passageway,
coengaging means on said members for limiting relative movement between said members for at least two longitudinal positions,
valve means in said members operative for connecting said upper and lower passageways in one of said positions to permit fluids to pass from one of said passageways to the other of said passageways and operative in another of said positions for closing said passageways from fluid communication with one another,
bypass means arranged for coupling to said tubular members,
said bypass means having a mandrel and housing,
said bypass mandrel and housing being relatively movable between expanded and contracted positions and including valve means providing a fluid communication path between the exterior and interior of the well apparatus in one of said positions, and
means for restricting relative movement between said bypass mandrel and housing when said bypass valve means is closed.

8. Apparatus in a well bore containing a well fluid for flow testing the well including:

telescopically arranged tester members movable between spaced longitudinal positions,
valve means in said tester members for controlling flow through said tester members in said positions,
packer means including telescopically mounted members, and a packer element disposed on one of said packer members and arranged to be expanded by relative motion between said telescoping packer members,
means for releasably holding said telescoping packer members against movement when said packer element is expanded,
bypass valve means intermediate said tester members and said packer members for providing a fluid communication path between the annulus spaces in said well bore above and below said packer means,
said bypass means further including telescopically arranged tubular members movable between expanded and contracted positions,
means for delaying the movement of said bypass members to a position wherein said fluid communication path is provided, and
safety joint means intermediate said tester members and said packing means, said safety joint means including telescoping members mounted for longitudinal movement and arranged to selectively resist rotative movement,
said safety joint members capable of being rendered separable by a series of longitudinal and rotative motions on one of said members,
said safety joint means, bypass means, packer means and tester means each having a full-opening bore therethrough.

9. Apparatus for testing earth formations in a well bore containing well fluids comprising telescopically arranged inner and outer tubular members adapted for coupling between a string of pipe and packer means,

said inner tubular members having a removable plug portion normally closing off its bore, a test port above said plug portion, and seal means on said inner tubular members below said port,
said outer tubular member having a bore portion with longitudinal spaced openings in fluid communication with one another through the body of said tubular member,
means permitting longitudinal movement of said members relative to one another between positions where said seal means is above said spaced openings and intermediate of said spaced openings,
abutment means on said members engageable in each of said positions for transmitting downwardly directed forces from said inner member to said outer member, and shear means for releasably securing said plug portion within the bore of said inner tubular member so that said plug portion can be removed to provide a straight-through access passageway through said members.

10. A well testing tool comprising: first and second telescopically arranged members adapted for coupling in a tool string, said members having passageways and valve means for selectively placing said passageways in communication, means securing said members to one another, at least one abutment means mounted on one of said members for rotation relative to both of said members, at least one abutment means mounted on the other of said members, and index means including cam means cooperable between said first mentioned abutment means and one of said members for positioning said abutment means in engagement in one longitudinal position of said members whereby forces in one direction can be transmitted from one of said members to the other through said abutment means and for rotating said first mentioned abutment means relative to both of said members in response to longitudinal motion of one of said members to disengage said abutment means to permit relative movement of said members to another longitudinal position.

11. A well testing tool comprising first and second telescopically arranged members adapted for coupling in a well string, said members having passageways and valve means for selectively placing said passageways in communication, means securing said members to one another, at least one abutment means mounted on one of said members for rotation relative to both of said members, at least one abutment means mounted on the other of said members, index means for positioning said abutment means in engagement in one longitudinal position of said members for transmitting forces in one direction and operable to disengage said abutment means to permit movement of said members to another longitudinal position, and means on said members engageable in said other longitudinal position for transmitting forces in said one direction.

12. A flow evaluating tool for use in a well bore, said tool having inner and outer tubular members telescopically movable between first and second relative positions, said members having passageways and valve means placing said passageways in communication in one of the relative positions and out of communication in the other of the relative positions, a first abutment on one of said members, a second abutment on the other of said members engageable with said first abutment when said members are in the relative position where said passageways are out of communication so that downward forces can be transmitted from one member to the other, and index means separate from said abutment means for angularly displacing one of said abutments relative to the other to disengage said abutments so said members can be moved to the relative position where said passageways are placed in communication.

13. A flow evaluating tool for use in a well bore, said tool having inner and outer tubular members telescopically movable between first and second relative positions,

said members having pasageways and valve means placing said pasageways in communication in one of the relative positions and out of communication in the other of the relative positions, one of said members having a rotatable portion, a first abutment on said rotatable portion, a second abutment on the other of said members engageable with said first abutment when said members are in the relative position where said pasageways are out of communication so that downward forces can be transmitted from one member to the other, index means for angularly displacing one of said abutments relative to the other to disengage said abutments so that said members can be moved to the relative position where said pasageways are placed in communication, and a third abutment on said one of said members longitudinally spaced from said first abutment and engageable with said other of said members when said members are in the relative position where said pasageways are placed in communication so that downward forces can be transmitted from one member to the other.

14. A well tool comprising: inner and outer tubular members telescopically movable between first and second relative positions, said members having pasageways and valve means placing said pasageways in communication in one of the relative positions and out of communication in the other of the relative positions; a first abutment on one of said members; a second abutment on the other of said members engageable with said first abutment when said members are in the relative position where said pasageways are out of communication so that downward forces can be transmitted from one member to the other; and index means, including a part rotatable relative to said members solely responsive to longitudinal reciprocation of one of said members, for angularly displacing one of said abutments relative to the other to disengage said abutments so that said members can be moved to the relative position where said pasageways are placed in communication.

15. Apparatus for testing earth formation conditions in a well bore containing well fluids comprising: flow conduit means extendible in the well bore to the earth formations to be tested and including a string of pipe, tester means, and packing-off means, said packing-off means being below said tester means and arranged to selectively isolate a section of the well bore from the well fluid therein, said tester means including telescoping tubular members, one of said members having relatively rotatable parts and longitudinally spaced abutments, the other of said members having an abutment, and indexing means between one of said parts and said other member for selectively positioning said other member abutment on one of said abutments on said parts by longitudinal movement of said other member and rotation of one of said parts.

16. Apparatus for testing earth formation conditions in a well bore containing well fluids comprising: packing-off means dependently coupled to tester means, said packing-off means being arranged to selectively isolate a section of the well bore from the well fluid therein, said tester means having telescopically arranged members adapted for coupling between a string of pipe and said packing-off means and longitudinally movable between contracted and expanded positions, valve means in said tester means for selectively opening said tester means to fluid flow in one of said positions and closing said tester means to fluid flow in the other of said positions, one of said tester members having relatively rotatable parts, said parts and said other members respectively having abutment means providing at least two longitudinal positions of butment, and means interacting between one of said parts and said other tester member for selectively positioning said abutment means in said positions.

17. Apparatus for testing earth formation conditions in a well bore containing well fluids comprising: packing-off means dependently coupled to tester means, said pack-

ing-off means being arranged to selectively isolate a section of the well bore from the well fluid therein by the application of a downward force, said tester means having telescopically arranged members adapted for coupling between the string of pipe and said packing-off means and longitudinally movable between contracted and expanded positions, valve means in said tester means for selectively opening said tester means to fluid flow in one of said positions and closing said tester means to fluid flow in the other of said positions, one of said tester members having relatively rotatable parts, said parts and said other members respectively having abutment means providing at least two longitudinal positions of abutment, indexing means interacting between said parts and said other tester member for selectively positioning said abutment means in said positions whereby downward force can be applied in each of said positions, and means for delaying telescopic movement of said tester members to a position opening said valve means.

20 18. Apparatus in a well bore containing well fluid for flow testing the well including: telescopically arranged tester members movable between spaced longitudinal positions, valve means in said tester members for controlling flow through said tester members in said positions, packer means including telescopically mounted members, and a packer element disposed on one of said packer members and arranged to be expanded by relative motion between said telescoping packer members, means for releasably holding said telescopic packer members against movement when said packer element is expanded, by-pass valve means intermediate said tester members and said packer members providing a fluid communication path between the annular spaces in said well bore above and below said packer means, said by-pass means further including telescopically arranged tubular members movable between expanded and contracted positions, means for delaying the movement of said by-pass members to a position wherein said fluid communication path is provided, and safety joint means operable in response to manipulation of the string of pipe.

19. A well tool for use in a well bore, a first tubular member having a bore therein, a second tubular member having a longitudinal opening therethrough and slidably received for telescoping movement within said first tubular member between at least two longitudinal relative positions, removable closure means in one of said members for dividing said bore and longitudinal opening into an upper and lower passageway, means for limiting relative movement between said members in said at least two positions so that forces on one of said members can be transmitted to the other of said members in each of said relative positions, valve means in said members operative for connecting said upper and lower passageways in one of said positions to permit fluids to flow from one of said passageways to the other of said passageways and operative in another of said positions for closing said passageways from fluid communication with one another, and shear release means connecting said closure means to said one of said members so that said closure means can be forceably removed by dropping a weighted member through the inner tubular member to provide said members with a longitudinal access passageway therethrough.

20. A well tool for use in a well bore, a first tubular member, a second tubular member having a longitudinal opening therethrough and slidably received for telescoping movement within said first tubular member, barrier means in one of said members dividing said longitudinal opening through said member into an upper and lower passageway, means on said members for limiting relative movement between said members for at least two longitudinal positions, said means including spaced abutment means arranged for engagement in spaced longitudinal positions for transmitting downward forces in said longitudinal positions, valve means in said members operative for connecting said upper and lower passageways in one

of said positions to permit fluids to pass from one of the said passageways to the other of said passageways and operative in said other position for closing said passageways from fluid communication with one another, and index means, separate from said abutment means and operable in response to relative movement of said first and second tubular members, to permit selective engagement of said abutment means.
